FILM REEL

Charles Edward McAuley, Unionville, N. Y.

Application September 14, 1939, Serial No. 294,841

5 Claims. (Cl. 242—74)

The present invention relates to a film reel and particularly relates to a film reel for use in motion picture projectors.

Although not particularly limited thereto, the present invention will be particularly described in its application to the usual 8 mm. and 16 mm. moving picture reels now widely utilized in connection with home projectors for carrying and utilizing exposed and developed film.

10 In connection with many of these reels it is desirable to secure readily to the reel the end of the film to be wound upon the reel and to do this without complicated clamping mechanisms, perforation engaging means or bending the end of the film by inserting it into a slot or slots in the core of the reel.

It is, therefore, among the objects of the present invention to provide a reel of the character above described having side flanges and a core 20 in which reel it will be readily possible to engage the end of the film at the core without the necessity of clamps, perforation engaging means or special constructions without damaging or marring the end of the film.

25 In accomplishing this object, it has been found undesirable to provide resilient clamping means as these have a tendency to weaken the film and also decrease its life and it is among the objects of the present invention to provide an improved 30 clamping arrangement of the character described in which the end of the film will be engaged without resultant clamping by an effective, yet inexpensive device readily assembled with the types of reels now in use, which may be 35 readily manipulated by the user.

Still further objects and advantages will appear from the more detailed description set forth below it being understood, however, that this more detailed description is given by way of illustration since various changes therein may be 40 made by those skilled in the art without departing from the scope and spirit of the invention.

In accomplishing the above objects, it has been found most desirable to form the reel and 45 side plates of stamped sheet metal with a core attached to said side plates and having suitable engagements with said side plates by teeth extending out from the core and projecting through openings in said side plates.

50 Between the cores and the side plates are non-resilient engaging means preferably having the form of plates which may be provided with bosses or enlargements adjacent and outside of the juncture of the core and the side plates.

55 These embossments may be relatively short

and extend into recesses in the edge of the core or they may be relatively wide and extend part of or the entire periphery of the core.

Referring to the drawings which illustrate several of the various possible embodiments of the present invention, but to which the present invention is by no means restricted since the drawings are merely by way of illustration and not by way of limitation.

Figure 1 is a top view of one form of reel according to the present invention showing the side plates, core and added winder plates on edge;

Figure 2 is a side elevational view of the reel of Figure 1;

Figure 3 is a fragmentary transverse sectional view on the line 3—3 of Figure 1.

Figures 4 and 5 are respectively fragmentary transverse sectional views on the line 4—4 and 5—5 of Figure 3 upon an enlarged scale as compared with Figure 3.

Figure 6 is a perspective view of the core before assembly with the side plates upon an enlarged scale as compared to Figure 3;

Figure 7 is a plan view of a plate construction;

Figure 8 is an elevational view of the side of an alternative reel construction;

Figures 9 and 10 are fragmentary cross sectional views on the lines 9—9 and 10—10 upon an enlarged scale as compared to Figure 8;

Figure 11 is a perspective view of a core and of the reel of Figures 8 to 10 before attachment to the side plates.

Figure 12 is a plan view of the plate of Figures 8 to 10 before attachment between the core and the side plates.

Figures 13, 14 and 15 show an alternative embodiment Figure 13 being a fragmentary transverse sectional view of a reel, Figure 14 being a plan view of the plate construction of Figure 13 and Figure 15 being a sectional view on the line 15—15 of Figure 14.

Referring to the embodiment of Figures 1 to 7, the reel is provided with side plates A, the core B and the intermediate wind plate C.

As shown in Figure 2, each of the plates is provided with the circular edge 10, the cut-outs 11, 12, 13, 14 and 15.

The cut-outs are preferably so arranged as to 50 permit inspection of the film without unduly decreasing the amount of said surface available to hold the film in position between the side plates A.

The opening 13 may be provided with the grad-

uations 16 indicating the amount of film wound upon the reel.

For this purpose, the opening 13 is provided with an extension 17 which carries the 400 foot mark.

The center opening 15 is designed to fit upon a spindle and is provided with outstanding extensions 18.

It will be noted that one of the flanges A is marked as "Front" at 19 since this is the side which is to be on the outside of the spindle.

The other side is provided with a similar square opening 20 having the extensions 21 at 90° to the extensions 18. It will be noted that the openings 13 and 14 extend inwardly toward the center of the reel at 22 inside of the core B.

As shown, the core B in Figure 6 is formed of a rounded piece of sheet metal 23, the ends of which are brought together to form a slot at 24.

20 The side edges 25 abut the inside faces of the plates A and the extensions 26 are designed to fit into the openings 27 in the sides of the reel to form a firm attachment on the sides of the reel and side core B. The extensions may be turned 25 over or riveted as shown at 27a to secure a tight connection.

Between the core B and the side plates A are positioned the plates C having the outstanding portions or ears 28 and having the recessed portions 29 corresponding to the portions 22 of the recesses 13 and 14.

The center opening 30 is sufficiently large to extend outside of the openings 15 and 20 and their extensions 18 and 21 in the side plates A.

35 The slots 31 correspond to the slots 27 and receive the projections 28 of the core B.

The embossments 32 are positioned at the ends of each slot 31 and they extend down inside of the core and fit into the recess 33 at the edge of 40 the core as best shown in Figure 4.

It is readily apparent the reel may be readily assembled and in operation the edge of the film may be caught by the pairs of embossments 32.

45 The plates A and the core B are made of relatively thick sheet aluminum or steel or other alloys which are self sustaining or non-resilient while the core plates C are made up of thin non-resilient sheet metal which readily bends and is quite soft and catches the film without resilient 50 action.

55 In the embodiment of Figures 8 to 12 (similarly functioning parts being indicated by the same numerals and letters as indicated in the embodiment of Figures 1 to 7, however primed), the side plates A' are of the same construction as the plates A of Figures 1 to 7 and the core is also of the same construction as the core of Figure 6 except that the recesses 33 have been eliminated.

In the core plate the embossments, instead of 60 being placed at the side of the slot, are placed as indicated at 32' extending entirely outside of the slots 31'.

The inner edges 40 of the embossments 32 will rest upon the outside face of the core, as indicated 65 best in Figure 10 and will be cut away to form an edge at 41 over the slots 31' (see particularly Figures 9 and 10).

70 In the embodiment of Figures 13 to 15 (similarly functioning parts being indicated by the same numerals provided with a superior "2"), the engagement means is formed by providing two parallel ridges 32² in the plates to be inserted between the core B² and the side plates A².

In all cases, the plates C to C² are non-resilient 75 and of a relatively soft sheet metal material.

It is apparent the specific illustrations shown above have been given by way of illustration and not by way of limitation and that the structures above described are subject to wide variation and modification without departing from the scope or intent of the invention, all of which variations and modifications are to be included within the scope of the present invention.

What is claimed is:

1. A film reel comprising sheet metal side flanges with openings therein, a sheet metal core consisting of a strip of metal which has been turned into a cylindrical form, and winder plates having a plurality of spaced fins projecting outwardly beyond the core, said plates being held 15 between said flanges and core, each of the fins of said plates having spaced embossed projections extending axially inwardly positioned adjacent the outside edges of said fins and at the core, said projections serving to catch the end of the film and said core having recesses receiving said projections.

2. A film reel comprising sheet metal side flanges with openings therein, a sheet metal core consisting of a strip of metal which has been 25 turned into a cylindrical form, and winder plates having a plurality of spaced fins projecting outwardly beyond the core, said plates being held between said flanges and core, each of the fins of said plates having spaced embossed projections extending axially inwardly positioned adjacent the outside edges of said fins at the core, said projections serving to catch the end of the film and said core having tongues extending 30 axially outwardly and said flanges having openings receiving said tongues, and said projections being positioned on each side of said tongues and openings.

3. A film reel comprising sheet metal side flanges with openings therein, a sheet metal core 40 consisting of a strip of metal which has been turned into a cylindrical form, and winder plates having a plurality of spaced fins projecting outwardly beyond the core, said plates being held between said flanges and core, each of the fins of said plates having spaced embossed projections extending axially inwardly positioned adjacent the outside edges of said fins and at the core, said projections serving to catch the end of the film and said fins and said flanges having a 45 plurality of arcuate slots, one being provided for each fin and said arcuate slots being placed on a diameter corresponding to the diameter of the sheet metal core and said core having spaced tongues along the outside edges thereof projecting through said slots and connected to said flanges at said slots.

4. A film reel comprising sheet metal side flanges with openings therein, a sheet metal core 50 consisting of a strip of metal which has been turned into a cylindrical form, said flanges being provided with film catching means including spaced radial embossed non-resilient projections extending axially inwardly positioned at the core, said core having tongues extending axially outwardly and said flanges having openings receiving said tongues, and said projections being positioned on each side of said tongues and openings, said embossed projections serving to catch the end of the film and said core having recesses adjacent said side flanges through which said projections extend.

5. A film reel comprising sheet metal side flanges with openings therein, a sheet metal core 55 consisting of a strip of metal which has been 60

turned into a cylindrical form, said flanges being provided with film catching means including spaced embossed radial non-resilient projections extending axially inwardly positioned at the core, said flanges having a plurality of spaced arcuate slots, said arcuate slots being placed on a diameter corresponding to the diameter of the sheet metal core and said core having spaced tongues

along the outside edges thereof projecting through said slots and connected to said flanges at said slots, said embossed projections serving to catch the end of the film and said core having recesses adjacent said side flanges through 5 which said projections extend.

CHARLES EDWARD McAULEY.
